CLAIM

I claim the ornamental design for field glasses, as shown and described.

DESCRIPTION

FIG. 1 is an upper perspective view of field glasses showing my new design.

FIG. 2 is a lower perspective view thereof.

FIG. 3 is a rear perspective view thereof.

FIG. 4 is another lower perspective view thereof.

FIG. 5 is a front view thereof.

FIG. 6 is a rear view thereof.

FIG. 7 is a left view thereof.

FIG. 8 is a right view thereof.

FIG. 9 is a top view thereof; and,

FIG. 10 is a bottom view thereof.

The broken lines represent portions of the field glasses and form no part of the claimed design. The shade lines shown represent surface shading and not surface ornamentation, color, or material type.
